UNITED STATES PATENT OFFICE.

JOHN F. O'CONNOR, OF CHICAGO, ILLINOIS, ASSIGNOR TO WILLIAM H. MINER, OF CHAZY, NEW YORK.

ANTIFRICTION-BEARING.

1,314,014.

Specification of Letters Patent. Patented Aug. 26, 1919.

Application filed November 22, 1918. Serial No. 263,864.

To all whom it may concern:

Be it known that I, JOHN F. O'CONNOR, a citizen of the United States, residing at Chicago, in the county of Cook and State of Illinois, have invented a certain new and useful Improvement in Antifriction-Bearings, of which the following is a full, clear, concise, and exact description, reference being had to the accompanying drawings, 10 forming a part of this specification.

This invention relates to improvements in anti-friction bearings.

The object of this invention is to provide an anti-friction bearing of the gravity 15 actuated type and especially adapted for use as a side bearing for railway cars and more specifically, the object of the invention is to provide novel means for insuring the return of the rocking element to normal position after each actuation of the bearing.

In the drawing forming a part of this specification, Figure 1 is a vertical, sectional view, taken through portions of body and truck bolsters of a railway car showing my 25 improvements applied thereto. Fig. 2 is a top plan view of the side bearing proper. And Fig. 3 is a vertical, sectional view, taken substantially on the line 3-3 of Fig. 1.

30 In said drawing, 10 denotes the under side of a body bolster and 11 the upper side of a truck bolster of a railway car. As shown, my improved side bearing is applied to the truck bolster and the same consists, 35 broadly, of a housing or base casting A, a rocker proper B, and a pair of pendulum elements C-C.

The base casting A is of substantially rectangular formation having upstanding side 40 walls 12-12 and inclined end walls 13-13. The base casting A is provided with flanges at the bottom thereof, as indicated at 14, by which it may be riveted to the truck bolster. The casting A is formed also with a bottom 45 wall 15 adapted to act as a bearing surface for the rocker B.

The rocker B, as shown, is provided with an upper cylindrical bearing surface 16 and a corresponding concentric lower bearing 50 surface 17, the two bearing surfaces 16 and 17 being connected by flat surfaces 18-18, preferably arranged tangential to the upper bearing surface 16. The rocker B is formed on each side thereof with 55 a normally vertically extending slot 19,

as clearly indicated in Figs. 1 and 3, and for lightness, the rocker B may be cored as indicated at 20-20. The flat faces 18 of the rocker are adapted to coöperate with the inclined end walls 13 of the base casting to 60 limit the rolling movement of the rocker, as will be evident from Fig. 1, where one extreme position of the rocker is shown in dotted lines.

Each pendulum member C is preferably 65 of plate-like form having a sector-like lower section, as indicated at 21, and an arm 22. On its outer side, each pendulum member C is provided with a circular boss 23 adapted to act as a pivot for the pendulum member, 70 said pivot boss 23 being mounted in a suitable bearing provided therefor in the side wall 12 of the base casting, as most clearly shown in Fig. 3. This may be accomplished by slotting the side walls of the base casting, 75 as indicated at 24. At their upper ends, the pendulum members C are provided with inwardly extending circular bosses 25 arranged to be seated within the corresponding vertical recesses 19 in the 80 rocker. The lower sector-like section of the element C is preferably extended below the bottom of the rocker and for this purpose the base casting A may be recessed as indicated at 26, to accommodate the pendulum 85 elements.

The normal position of the parts is as shown in full lines in Fig. 1. In operation, assuming that the truck bolster remains stationary and the body bolster moves to the 90 left as viewed in Fig. 1, the rocker will be shifted to the position shown by dotted lines. Simultaneously with the movement of the rocker, it is evident that the two pendulum elements C will be oscillated about 95 their respective pivot lugs 23 in such manner that the sector-like sections of the pendulum elements will be elevated to the dotted position shown in Fig. 1. Upon release of the actuating pressure, it is evident that 100 the rocker itself will tend to return to normal and this return movement will be greatly accentuated by the pendulum elements C acting through the lugs 25 that coöperate directly with the rocker B. By 105 employing the pendulum elements, the return of the rocker to normal is greatly facilitated and made more certain and in addition the mounting of the pendulum elements is such that they will serve to retain 110

the rocker in central position with respect to the base casting A and thus eliminate the necessity for the usual toothed engagement between the rocker and base casting.

5 I claim:

1. In an anti-friction bearing, the combination with a housing, of an anti-friction element disposed within the housing and adapted for rolling movement, and means 10 for insuring return of said element to normal position after each actuation thereof, said means including a member pivotally mounted on the housing, said member being eccentrically weighted and having a sliding 15 connection with said element.
2. In an anti-friction bearing, the combination with a housing, of an anti-friction element adapted for rolling movement, and a pendulum member pivotally mounted on 20 the housing, said pendulum member and anti-friction element having coöperating engaging means so arranged that upon rolling movement of the element, the pendulum member is shifted to a position of unstable 25 equilibrium and is thereby adapted to return the anti-friction element to normal upon release of the actuating pressure.
3. In an anti-friction bearing, the combination with a housing having a bottom 30 bearing wall, of a rocker disposed within the housing and adapted to roll on said bearing wall, and a pendulum member pivotally mounted on the housing and having a sliding pivotal connection with the rocker.
- 35 4. In a side bearing for railway cars, the combination with a base casting adapted to be secured to a truck bolster, of a rocker disposed within said base casting, a pendulum member disposed at each side of the rocker,

each pendulum member being pivotally 40 mounted on the base casting and having a sliding pivotal connection with the rocker, the rocker being adapted to oscillate the pendulum members about their pivotal connections with the base casting when the rocker 45 is actuated.

5. In a side bearing for railway cars, the combination with a hollow base casting having side walls, the side walls being provided with bearing seats, of a rocker mounted 50 within the base casting between said side walls, pendulum members at each side of the rocker and located between the rocker and the side walls of the base casting, each pendulum member having a bearing pivot stud 55 coöperable with the bearing seat of the adjacent side wall, and means for slidably connecting the rocker with the pendulum members so arranged that movement of the rocker to either side of normal causes oscillation of the pendulum members relatively to the base casting.

6. In a side bearing for railway cars, the combination with a base casting having side, end and bottom walls, of a rocker within 65 said base casting and bearing upon said bottom wall, the end walls of said casting being arranged to limit the rolling movement of the rocker, pendulum members on each side of the rocker pivotally mounted on the side 70 walls of the base casting, said rocker having elongated slots in the sides thereof, and said pendulum members having studs engaging in said slots of the rocker.

In witness that I claim the foregoing I 75 have hereunto subscribed my name this 1st day of Nov. 1918.

JOHN F. O'CONNOR.
